UNITED STATES PATENT OFFICE.

BENJAMAN F. NEDROW, OF ANACORTES, WASHINGTON, ASSIGNOR OF ONE-HALF TO
HAYWARD N. MARSHALL, OF SHAW ISLAND, WASHINGTON.

RELEASING-HOOK.

1,124,790.

Specification of Letters Patent.

Patented Jan. 12, 1915.

Application filed June 29, 1914. Serial No. 348,009.

To all whom it may concern:

Be it known that I, BENJAMAN F. NEDROW, a citizen of the United States, residing at Anacortes, in the county of Skagit and State of Washington, have invented certain new and useful Improvements in Releasing-Hooks, of which the following is a specification, reference being had to the accompanying drawings.

10 This invention relates to improvements in supporting hooks and more particularly to that class of supporting hooks which are generally designated as releasing hooks for boats and the like.

15 An object of this invention is the provision of a releasing hook comprising a pair of pivotally connected jaws which are suitably mounted in a supporting body, one of the jaws carrying a locking cam to lock the 20 jaws together, whereby a chain or other suitable carrying device will be detachably secured to the hook.

25 Another object of this invention is the provision of a releasing hook, comprising a pair of jaws pivotally connected together intermediate of their ends in a supporting body, one of the jaws carrying a cam lever for engagement with the other jaw, whereby 30 the hooked ends of the jaws may be opened or locked, as desired.

35 With these and other objects in view, my invention consists in certain novel constructions, combinations, and arrangements of parts to be hereinafter more fully described, claimed, and illustrated in the accompanying drawing, in which,

40 Figure 1 is a side elevation of my improved hook with one of the side bars removed, and showing the jaws in locked position; Fig. 2 is a similar view showing the jaws in open position; Fig. 3 is an edge view of the hook; and Fig. 4 is a sectional view on the line 4—4 of Fig. 1.

45 Referring more particularly to the drawing, my invention consists of a supporting body which comprises a pair of spaced parallel side bars 5, between the upper ends of which a spacing block 6 is secured, the spacing block having an upwardly extending eye 7 which projects above the upper ends of the side bars 5 for connection to a supporting chain 8. Each of the side bars 5 has an opening 9 formed therein adjacent its lower end, for the reception of the opposite

ends of a pivot pin 10 upon which the jaws 55 11 and 11' are pivotally mounted intermediate of their ends. Each of the jaws is provided with an inwardly extending apertured ear 12, the openings in the ears registering to receive the pivot pin 10, whereby the jaws 60 are pivotally mounted between the side bars 5 at their lower ends. Each of the jaws is formed with a hooked lower end 13 so that when the lower ends of the jaws are engaged with each other, an eye 14 is formed 65 therebetween for the reception of a chain or the like (not shown) which is connected at its opposite end to a boat or similar member (not shown) which the hook is desired to carry.

70 The jaw 11 has an opening 15 formed therein at its upper end, in which the upper end of a lever 16 is pivotally mounted on a pivot pin 17, the jaw 11 having a longitudinal groove 18 formed in its upper edge for 75 the reception of one edge of the locking lever 16 when in locked position. A cam shaped head 19 is formed on the upper end of the lever 16, the cam 19 projecting inwardly through the opening 15 for 80 engagement with the upper end of the jaw 11' whereby the upper ends of the jaws 11 and 11' are held in spaced relation with each other, to secure the hooked ends 13 locked against each other. An opening 20 is formed 85 in the lower end of the lever 16, to receive one end of a flexible cord 21, whereby the locking lever may be operated to allow separation of the hooked ends of the jaws.

90 In the practical use of my improved releasing hook, the supporting chain or other supporting device which is connected to the member to be carried by the hook, is placed between the lower hooked ends of the jaws when the locking lever 16 is in 95 raised position, whereupon the free end of the locking lever is lowered so that the inner edge thereof engages in the groove 18 in the outer edge of the jaw 11', whereby the cam 19 is moved into engagement with 100 the inner face of the jaw 11', to close the lower ends of the jaws to securely hold the supporting member therebetween. When it is desired to open the jaws of the device, it is merely necessary to pull upwardly upon 105 the cord 21 which is connected to the free end of the lever 16, so that the cam 19 is removed from engagement with the inner

face of the jaw 11' to allow the hooked ends of the jaws to separate from each other and release the member supported thereby.

From the above description, taken in connection with the accompanying drawing, it will be seen that I have provided a releasing hook which may be quickly locked to any member which it is desired to carry, and which may be quickly disengaged therefrom by an upward pull upon the locking lever 16. It will be understood that the releasing hook may be used in connection with logging trains or in connection with any other device in which hooks of this character are employed.

Having thus fully described my invention, what I desire to secure and claim by Letters Patent, is:—

1. A device of the character described comprising a supporting body, a pair of jaws pivotally mounted intermediate of their ends in said body, one end of each of said jaws being provided with a hooked portion, and a cam lever carried by one of the jaws adjacent its other end, said cam lever being adapted for engagement against the adjacent end of the other jaw, to detachably hold the hooked portions of the jaws in closed position.
2. A device of the class described comprising a supporting body, a pair of pivotally connected jaws pivotally mounted in the body, the outer end of each jaw projecting from the body and being provided with a hooked portion, the inner end of one of the jaws having an opening formed therein, a lever pivotally mounted at one end in said opening, and an inwardly extending cam head formed on said end of the lever for engagement with the adjacent end of the

other jaw, whereby the hooked portions of the jaws may be detachably held in closed position.

3. A releasing hook comprising a supporting body, a pivot pin disposed through the body, a pair of jaws pivotally mounted intermediate of their ends upon said pivot pin, the outer end of each of said jaws projecting from the body and being provided with a hooked portion, the hooked portions of said jaws coöperating to form an eye when the jaws are in closed position, and a cam lever pivotally connected to the inner end of one of said jaws, said cam lever being adapted for engagement against the adjacent end of the other jaw, whereby the hooked portions of the jaws may be detachably held in closed position.

4. A device of the class described comprising a pair of spaced side plates connected together at one end, a pivot pin projecting through said side plates at their other end, a pair of jaws pivotally mounted intermediate of their ends upon said pivot pin between said side plates, the lower ends of said jaws being hooked and projecting below the lower ends of said side plates, one of said jaws having an opening formed therein at its upper end, a lever pivotally mounted at its upper end in said opening, and a cam head formed on the upper end of said lever for engagement with the upper end of the other jaw, as and for the purpose described.

In testimony whereof I hereunto affix my signature in the presence of two witnesses.

BENJAMAN F. NEDROW.
